UNITED STATES PATENT OFFICE.

CORNELIUS KNUDSEN, OF COPENHAGEN, DENMARK, ASSIGNOR TO CHARLES JOHN WILSON, OF SAN FRANCISCO, CALIFORNIA.

CIGAR-TIP CUTTER.

SPECIFICATION forming part of Letters Patent No. 366,172, dated July 5, 1887.

Application filed April 22, 1887. Serial No. 235,522. (No model.)

To all whom it may concern:

Be it known that I, CORNELIUS KNUDSEN, of Copenhagen, Kingdom of Denmark, have invented an Improved Cigar-End Cutter, of 5 which the following is a specification.

The invention relates to those cigar-end cutters which are used principally in retail cigar-stores for the convenience of purchasers who desire to cut off the mouth end of the 10 cigar before lighting it.

The invention consists in an improved combination of parts constituting the cutter, which hereinafter is more specifically described and claimed.

15 In the accompanying drawings, forming part of this specification, Figure 1 is a front elevation of my device, with parts hidden shown in dotted lines. Fig. 2 is a plan of the same. Fig. 3 is an end view of the device. Fig. 4 is a sectional plan view.

20 In all the figures the same letters of reference are used to indicate the same parts.

A is the dish to catch the cut-off ends of the cigars as they fall from the cutters. It is 25 made of metal, either sufficiently heavy to withstand the operation of the cutters without displacement, or it may be made light and be fastened to the store-counter by wood screws, as preferred.

30 B is a hollow standard or pillar firmly secured to the dish by a tap-screw, b, as shown, at about the middle. This standard contains a spiral spring, C, (shown in dotted lines, Fig. 1,) which winds around the stem of the 35 cutter-head D, which passes down into the hollow part of the standard. The tendency of the spring is to raise the cutter-head when freed from the downward pressure of the operating-lever. The standard B terminates in 40 two side flanges, B' B', which are given a triangular shape in the drawings. Each lower corner of both of these flanges is provided with a countersunk aperture, b', which receives the tip ends of the cigars as they are held below

45 the cutter-blade in the act of chopping off their ends. There are attached to the cutter-head—one on each side—two cutter-blades, E, each being long enough to overlap the aper-

tures in the side flanges. The cutters may be made to cut a straight cut or a V-shaped cut, 50 as preferred, both styles of cutters being shown in the drawings.

F is the operating-lever—a sort of two-horned cam—which is pivoted on the pin G, which is supported by being driven through 55 the two side flanges, B' B'. The shape of the cam part of this double-handled lever is such as to cause the cutter-head to be pressed down, whichever horn of the lever is pushed downward. The shape is indicated by the dotted 60 lines.

I show balls H H on the points of the operating-lever; but any other suitable style of handle may be adopted.

The operation is simple, and as follows: The 55 cigar is inserted into one of the apertures and held there. Either one of the horns of the lever is then pressed downward, and the cutting-knives will slide past the orifices and cut off any projecting cigar-tip which may be held in 70 either of the four apertures with which the machine is provided.

I do not claim any particular shape for the cutting-knives, nor do I claim, in a broad sense, the combination of cutting-knives and 75 holder for the cigar; but

What I claim as my invention, and desire to secure by Letters Patent, is—

The cigar-tip cutter herein described, consisting, essentially, of the hollow pillar B, suitably supported and having side flanges, B' B', and apertures b', the vertically-moving cutter-head D, having its stem inserted into the hollow of the standing pillar and being provided with cutting-blades E E, the spiral spring C, 85 winding around the stem of the cutter-head and supporting the same, and the operating cam-lever F, bearing upon and pressing down the cutter-head when actuated, to the effect of clipping off the cigar-tips passed through 90 apertures b', the whole arranged and operating substantially as described.

CORNELIUS KNUDSEN. [L. S.]
